UNITED STATES PATENT OFFICE

105,428

DESIGN FOR A DOOR MAT OR SIMILAR ARTICLE

Durward A. Bahr, Oberlin, Ohio

Application April 25, 1936, Serial No. 62,310

Term of patent 14 years

To all whom it may concern:

Be it known that I, Durward A. Bahr, a citizen of the United States, residing at Oberlin, in the county of Lorain and State of Ohio, have invented a new, original, and ornamental Design for a Door Mat or Similar Article, of which the following is a specification, reference being had to the accompanying drawing, forming a part thereof.

In the drawing, Fig. 1 is a perspective view of a door mat or similar article embodying my new design; Fig. 2 is a section taken on the plane indicated by the line 2—2 in Fig. 1.

The dominant features of my design reside in tapering ribs, the height of each of which is substantially double the width at the base together with fillets at the base of the ribs of substantially the same width as the ribs at the base and a base having a substantially flat bottom and a thickness which is also substantially equal to the width of the ribs at the base.

I claim:

The ornamental design for a door mat or similar article, substantially as shown and described

DURWARD A. BAHR.
